9 Sheets-Sheet 4

<img alt="Technical drawing of a mechanical assembly labeled Fig. 7. The drawing shows a top-down view of a rectangular frame 70 containing a grid of components. A circular component 98 is centered within the frame. A vertical rod 94 extends from the center of the circular component 98. A horizontal rod 95 is positioned to the right of the frame 70, with a vertical rod 96 extending from its center. Various reference numerals are used to label parts: 104, 103, 98, 99, 94, 101, 97, 93, 92, 106, 100, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 70559, 70560, 70561, 70562, 70563, 70564, 70565, 70566, 70567, 70568, 70569, 70570, 70571, 70572, 70573, 70574, 70575, 70576, 70577, 70578, 70579, 70580, 70581, 70582, 70583, 70584, 70585, 70586, 70587, 70588, 70589, 70590, 70591, 70592, 70593, 70594, 70595, 70596, 70597, 70598, 70599, 70600, 70601, 70602, 70603, 70604, 70605, 70606, 70607, 70608, 70609, 70610, 70611, 70612, 70613, 70614, 70615, 70616, 70617, 70618, 70619, 70620, 70621, 70622, 70623, 70624, 70625, 70626, 70627, 70628, 70629, 70630, 70631, 70632, 70633, 70634, 70635, 70636, 70637, 70638, 70639, 70640, 70641, 70642, 70643, 70644, 70645, 70646, 70647, 70648, 70649, 70650, 70651, 70652, 70653, 70654, 70655, 70656, 70657, 70658, 70659, 70660, 70661, 70662, 70663, 70664, 70665, 70666, 70667, 70668, 70669, 70670, 70671, 70672, 70673, 70674, 70675, 70676, 70677, 70678, 70679, 70680, 70681, 70682, 70683, 70684, 70685, 70686, 70687, 70688, 70689, 70690, 70691, 70692, 70693, 70694, 70695, 70696, 70697, 70698, 70699, 70700, 70701, 70702, 70703, 70704, 70705, 70706, 70707, 70708, 70709, 70710, 70711, 70712, 70713, 70714, 70715, 70716, 70717, 70718, 70719, 70720, 70721, 70722, 70723, 70724, 70725, 70726, 70727, 70728, 70729, 70730, 70731, 70732, 70733, 70734, 70735, 70736, 70737, 70738, 70739, 70740, 70741, 70742, 70743, 70744, 70745, 70746, 70747, 70748, 70749, 70750, 70751, 70752, 70753, 70754, 70755, 70756, 70757, 70758, 70759, 70760, 70761, 70762, 70763, 70764, 70765, 70766, 70767, 70768, 70769, 70770, 70771, 70772, 70773, 70774, 70775, 70776, 70777, 70778, 70779, 70780, 70781, 70782, 70783, 70784, 70785, 70786, 70787, 70788, 70789, 70790, 70791, 70792, 70793, 70794, 70795, 70796, 70797, 70798, 70799, 70800, 70801, 70802, 70803, 70804, 70805, 70806, 70807, 70808, 70809, 70810, 70811, 70812, 70813, 70814, 70815, 70816, 70817, 70818, 70819, 70820, 70821, 70822, 70823, 70824, 70825, 70826, 70827, 70828, 70829, 70830, 70831, 70832, 70833, 70834, 70835, 70836, 70837, 70838, 70839, 70840, 70841, 70842, 70843, 70844, 70845, 70846, 70847, 70848, 70849, 70850, 70851, 70852, 70853, 70854, 70855, 70856, 70857, 70858, 70859, 70860, 70861, 70862, 70863, 70864, 70865, 70866, 70867, 70868, 70869, 70870, 70871, 70872, 70873, 70874, 70875, 70876, 70877, 70878, 70879, 70880, 70881, 70882, 70883, 70884, 70885, 70886, 70887, 70888, 70889, 70890, 70891, 70892, 70893, 70894, 70895, 70896, 70897, 70898, 70899, 70900, 70901, 70902, 70903, 70904, 70905, 70906, 70907, 70908, 70909, 70910, 70911, 70912, 70913, 70914, 70915, 70916, 70917, 70918, 70919, 70920, 70921, 70922, 70923, 70924, 70925, 70926, 70927, 70928, 70929, 70930, 70931, 70932, 70933, 70934, 70935, 70936, 70937, 70938, 70939, 70940, 70941, 70942, 70943, 70944, 70945, 70946, 70947, 70948, 70949, 70950, 70951, 70952, 70953, 70954, 70955, 70956, 70957, 70958, 70959, 70960, 70961, 70962, 70963, 70964, 70965, 70966, 70967, 70968, 70969, 70970, 70971, 70972, 70973, 70974, 70975, 70976, 70977, 70978, 70979, 70980, 70981, 70982, 70983, 70984, 70985, 70986, 70987, 70988, 70989, 70990, 70991, 70992, 70993, 70994, 70995, 70996, 70997, 70998, 70999, 701000, 701001, 701002, 701003, 701004, 701005, 701006, 701007, 701008, 701009, 701010, 701011, 701012, 701013, 701014, 701015, 701016, 701017, 701018, 701019, 701020, 701021, 701022, 701023, 701024, 701025, 701026, 701027, 701028, 701029, 701030, 701031, 701032, 701033, 701034, 701035, 701036, 701037, 701038, 701039, 701040, 701041, 701042, 701043, 701044, 701045, 701046, 701047, 701048, 701049, 701050, 701051, 701052, 701053, 701054, 701055, 701056, 701057, 701058, 701059, 701060, 701061, 701062, 701063, 701064, 701065, 701066, 701067, 701068, 701069, 701070, 701071, 701072, 701073, 701074, 701075, 701076, 701077, 701078, 701079, 701080, 701081, 701082, 701083, 701084, 701085, 701086, 701087, 701088, 701089, 701090, 701091, 701092, 701093, 701094, 701095, 701096, 701097, 701098, 701099, 701100, 701101, 701102, 701103, 701104, 701105, 701106, 701107, 701108, 701109, 701110, 701111, 701112, 701113, 701114, 701115, 701116, 701117, 701118, 701119, 701120, 701121, 701122, 701123, 701124, 701125, 701126, 701127, 701128, 701129, 701130, 701131, 701132, 701133, 701134, 701135, 701136, 701137, 701138, 701139, 701140, 701141, 701142, 701143, 701144, 701145, 701146, 701147, 701148, 701149, 701150, 701151, 701152, 701153, 701154, 701155, 701156, 701157, 701158, 701159, 701160, 701161, 701162, 701163, 701164, 701165, 701166, 701167, 701168, 701169, 701170, 701171, 701172, 701173, 701174, 701175, 701176, 701177, 701178, 701179, 701180, 701181, 701182, 701183, 701184, 701185, 701186, 701187, 701188, 701189, 701190, 701191, 701192, 701193, 701194, 701195, 701196, 701197, 701198, 701199, 701200, 701201, 701202, 701203, 701204, 701205, 701206, 701207, 701208, 701209, 701210, 701211, 701212, 701213, 701214, 701215, 701216, 701217, 701218, 701219, 701220, 701221, 701222, 701223, 701224, 701225, 701226, 701227, 701228, 701229, 7012210, UNITED STATES PATENT OFFICE.

SAMUEL STEWART, OF BIRMINGHAM, ALABAMA, ASSIGNOR OF ONE-HALF TO JAMES M. COSPER, OF GADSDEN, ALABAMA.

PIG-BED-MOLDING MACHINE.

Application filed February 5, 1923. Serial No. 616,919.

To all whom it may concern:

Be it known that I, SAMUEL STEWART, a citizen of the United States of America, residing at Birmingham, in the county of Jefferson and State of Alabama, have invented certain new and useful Improvements in Pig-Bed-Molding Machines, of which the following is a specification.

My invention relates to a pig bed molding machine which is adapted to perform mechanically all of the work required to prepare and form the molds bed for pig iron.

My invention contemplates, in its preferred embodiment, the combination in a traveling machine of all of the various instrumentalities required for preparing the sand bed in the best possible manner in advance of the mold roller so that the latter can most effectively perform its work, and to this end the mechanism comprises novel and effective means which in respective order will first plow the sand bed and remove pigs or pieces of iron left in the bed from the previous run; next will screen the sand and deposit it back in the bed, this operation preferably comprising the use of elevating buckets which raise practically all of the sand used in making the molds and pass it back through a screen which collects and removes from the sand foreign matter not caught by the scrap plows; next, using means such as a magnetic scrap collector to remove metallic particles which pass the screen; next grading the screened sand bed and adding such additional sand as may, from time to time be required to maintain the desired grade of the sand bed; next by means of a series of plows, one immediately in advance of and aligning with the runner mold and each pig mold, opening up the bed so as to eliminate as far as possible duty on the mold roller; and next utilizing a mold roller and designing it to form in the plow tracks the pig molds which lie level as formed in the sand bed.

My invention moreover contemplates the provision of means for the adjustment of the various mechanisms to the end that they may be set in their different operating positions or raised to inoperative position when the machine is not in operation.

A further distinctive feature of my invention is gearing the machine on each side

to racks which hold its transverse axis at right angles always to its line of travel, and in so co-relating the drive to the rack gears and the mold wheel that they shall have similar peripheral speeds.

A further distinctive feature is the formation of the runner mold wheel in sections at right angles to its axis and the mounting of said sections for rotation independently of each other and of the mold roller, so as to avoid any objectionable dragging of this mold wheel through the sand.

A further feature of my invention relates to mounting, in a self contained machine of the character described, a water tank with conveniently arranged sprays for moistening the sand to the desired extent and at the desired points relative to the several sand treating mechanisms.

A further distinctive feature is the provision of cam means, controlled by the pig mold roller and adapted automatically to raise and lower the sand plows in advance of said roller so as to reduce the depth of their cut at the points where the recessed patterns forming the wall behind each sow would strike, thus causing both the sow and pig patterns to perform substantially equal duty though penetrating to different depths below the initial grade of the sand bed.

A further distinctive feature is to so modify the curvature, in transverse cross section, of the pig mold roller as to cause the prints formed by the pig molds or patterns to lie horizontally in stepped levels which are disposed crosswise of a bed which bed must necessarily pitch sufficiently in a lengthwise direction to cause the metal to follow down the runner.

My invention also contemplates the effective provision of means for controlling the raising and lowering of the various sand treating appliances from an operator's platform and of incorporating in the drive for the machine means for enabling it to be returned at relatively fast speed after forming a pig bed.

My invention also particularly contemplates means for facilitating the angular adjustment of the sand treating and molding mechanism to accommodate it to pig beds having various lateral pitches, said adjustment being accomplished at the same time for

all parts by raising or lowering either side of their supporting frame relatively to its supporting track wheels, and thus avoiding the necessity for adjusting the various parts 5 separately.

My invention also comprises the novel details of construction and arrangements of parts which are hereinafter more particularly described in the accompanying specification, and which are pointed out in the appended claims, reference being had to the accompanying drawings, which form a part of this specification, and which seek to illustrate only what I regard as the preferred 15 embodiment of my invention.

In the drawings:—

Fig. 1 is a plan view of the machine.

Fig. 2 is a side elevation of Fig. 1 with the rack pinions broken away.

Fig. 3 is a detail view showing the rack and pinion drive omitted from Fig. 2.

Fig. 4 is a rear end elevation of the drive to the pinions.

Fig. 5 is a cross-sectional view taken on the 25 line 5—5 of Fig. 2 showing the main mold roller and the drive for adjusting it.

Fig. 6 is a sectional view taken on the line 6—6 of Fig. 2 showing in rear elevation the plows preceding the mold roller.

Fig. 7 is a sectional view taken on the line 30 7—7 of Fig. 2 and showing in rear elevation the shaking screens and their drive together with the operator's platform and control elements.

Fig. 8 is a cross-sectional view on the line 35 8—8 of Fig. 2 showing in rear elevation the sand elevator.

Figs. 9, 10 and 11 are enlarged side views 40 of portions of the machine, the three views respectively showing the rear end, the intermediate section and the forward end of the machine.

Fig. 12 is an enlarged cross-sectional view 45 through the mold roller.

Fig. 13 is an enlarged view of the mold roller showing the runner mold and a cross-sectional view through the pig bed.

Fig. 14 is a longitudinal cross-sectional view 50 of the molded pig bed.

Fig. 15 is a detail cross-sectional view of the sand bin and its sand discharge valve.

Figs. 16, 17, 18 and 19 are respectively 55 cross-sections, elevations and plan of the mold and bucket wheel elevator and the frame tilting mechanism.

Similar reference numerals refer to similar parts throughout the drawings.

The machine, as illustrated in its preferred embodiment, comprises a rigid marginal frame, preferably fabricated of structural iron or steel suitably braced to have the necessary rigidity and strength to support the operating mechanism as it travels back and forth over the pig bed on the 65 wheels 2 which at the rear are mounted on

a shaft 3 and at the front on a shaft 4, and which travel on tracks 5 suitably mounted on each side of the pig bed. On the overhung ends of the shaft 3 I mount pinions 6 which mesh with racks 7 disposed parallel with and adjacent to tracks 5. The shaft 3 is suitably supported in bearings 8 underhung from the sides of the frame and the pitch line of the pinions is equal to the diameter of the wheels 2 so that as the machine is moved the pinions and wheels will have the same peripheral speeds. The machine is preferably adapted to be driven by electric power. For this purpose I show an electric motor 9 suitably mounted at the rear end of the frame and having its gear 10 meshing a gear 11 on a countershaft 12 carrying at its overhung end a sprocket 13, which by means of a sprocket chain 14 drives a sprocket 15 fast on a shaft 16 journaled in the frame near the rear end thereof in bearings 17. The drive from this shaft 16, under the control of a clutch 18, can be adapted to move the machine in a forward direction by means of a sprocket 19 loose on shaft 16, chain 20 and sprocket 21 fast on the shaft 3, or by reversing the motor 9 to move the machine in a reverse direction and at a much higher rate of speed by means of a sprocket 22 loose on shaft 16, chain 23 and sprocket 24 also fast on shaft 3. By this means the machine can be driven forward slowly while forming the mold bed and can be returned quickly after completing its work.

The shaft 3 carries at each end a sprocket 25, each of which is connected by a chain 26 to a sprocket 27 on the mold roller shaft 28. This shaft 28 is mounted in journal boxes 29 which are free to slide vertically in guides 30, each being controlled in its adjustments by means of a pair of links 31, which links straddle the side I-beam of the frame, having eyes at their lower ends to receive hub extensions 29^a on the boxes 29 in which the shaft 28 turns, and being hung from a cross head 32 which is vertically adjustable in a stanchion 33 by a screw 34, which at its upper end is in threaded engagement with a beveled gear 35, which is held against raising or lowering by the stanchion. These gears 35 mesh with pinions 36 which are mounted on cross shafts 37, which shafts at their inner ends are provided with gears 38 which mesh gears 39 at each end of the shaft of an electric motor 40. The threads on the screws 34 are a reverse pitch to cause them to raise or lower the boxes simultaneously. This makes provision for the vertical adjustment of the mold roller to set it to the desired working level or to raise it out of operating position.

To control the pitch of the roller endwise or from side to side of the pig bed, the wheel shaft 3 at one side is shown mounted in a

journal box 41 which is free to slide vertically in the guides 42 forming part of the bearing 8, the vertical adjustments of the frame 1 relative to the box 41 being controlled by a pair of links 43 which engage the hub extensions 41^a on the box 41 and straddle the side of the frame 1, being at their upper ends hung from a cross head 44 on a screw 45 on which a worm wheel 46 is threaded. This worm wheel 46 is adapted to mesh a worm 47 operated by a hand wheel 48 on the worm shaft which turns in suitable bearings 49 on the stanchion 50 for the cross head. The worm wheel is held in position between the upper and lower bearings 51 in the stanchion 50. A similar adjusting rigging for the frame 1 relative to the journal box 41 for shaft 4 on the same side of the machine at the front is provided, so that by manipulating these worm gearings the side of the frame can be raised and lowered with all the mechanism carried thereby to give the desired lateral pitch to the machine as a whole and hence to the mold roller. Obviously such an arrangement may be provided for the axle boxes 41 on either side or both sides of the machine as desired.

A mold roller 52, the detail construction of which will be later described, is mounted fast on the shaft 28, and at both ends adjacent to the mold roller driving gears 27 I mount cams 53. These cams are symmetrical and have four high points spaced 90° apart and the mold roller is provided about its circumference with four axial series of pig mold patterns 54, each of which axial series of such patterns is co-ordinated with one of the high points of the cams 53. The cams engage and operate bell cranks 55 mounted in suitable bearings 56 on the frame and each connected at its free forward end by a swinging link 57 with an eye 58 fast to a cross member 59 mounted for vertical play in underhung guides or stanchions 60. The cross member 59 constitutes a plow carrier and has connected along its bottom edge in any suitable manner, a series of plows 61, one of which is disposed in alignment with each circumferential row of pig mold patterns 54 on the mold roller. The plows are so placed relatively to, and the points of the cams are so co-related with, the mold roller that the plows as they are raised and lowered will vary the depth of their cut to roughly correspond to the irregular contour of the patterns on the mold roller that will come into engagement therewith, so that the duty on the patterns, regardless of their height relative to a circle having the smallest diameter of the mold roller, will be practically uniform.

The mold roller carries at one end a runner mold wheel 62 and I mount in advance of this a plow 63 pivotally connected to

bearings 64 underhung from the frame. The plow is provided with an eye 65 to which an operating rod 66 is pivotally connected, this rod at its upper end being connected to a bell crank lever 67 pivoted to the sand bin 68 and adapted to be operated by a rod 69 leading forward of the machine to the operator's platform 70, where by means of one of the levers 71 the plow can be raised, lowered or set in any desired operating position. The runner mold wheel 62 being of uniform diameter does not require that this plow 63 be raised or lowered except when it is desired to run the machine back over the bed.

Immediately in advance of the plows and extending the full width of the mold roller is a sand bin 68 which has in its bottom a rotating sand valve 72 mounted on a shaft 74 journaled in suitable bearings 73 in the side walls of the bin. Fast on the outer ends of the valve shaft 74 is a sprocket wheel 75 driven by a sprocket chain 76 from a sprocket gear 77 on a counter-shaft 78 driven by gearing 78^a from an electric motor 79 mounted on the frame at one side. The cross section of the sand valve is illustrated more clearly in Fig. 6, and it will feed only intermittently as it is rotated. Its motor is started and the valve is driven when it is necessary to supply additional sand to make up the loss of sand from the bed. The bin 68 therefore contains only a supplemental supply of sand for replacement purposes. Along the bottom of the bin 68 I provide an extension wall 80 forming a chute for the sand and to the lower edge of this chute I connect by hinges 81 a grading plate 82 which is reinforced by a transverse angle iron 83 and which can be raised and lowered by rods 84 connected below to eyes 85 on the grading plate and above to bell crank levers 86 mounted on a shaft 87, and each having its free arm connected by a rod 88 to one of the operating levers on the operator's platform. The shaft 87 is mounted to turn in a hollow shaft 87^a which is journaled in suitable bearings in the ends of the sand bin 68 and the solid shaft 87 extends through the hollow shaft and has a bell crank 86 keyed to each overhung end thereof.

I mount on the shaft 87^a near each end a bell crank lever 86^a from each of which depends a rod 89 which is preferably tubular so that electric cables 90 can pass through one or both of these to a magnet 91 hingedly connected to the lower end of the rods 89 and disposed to travel in close proximity to the sand bed for the purpose of collecting small pieces of metal left in the screened sand. The magnet is in the form of a bar extending the full width of the bed and it can be raised and lowered as desired.

Immediately in advance of the magnet is a transversely disposed shaking screen preferably composed of a lower screen having

sides 92 suspended by links 93 pivotally mounted on a transverse I-beam 94 connected across the frame. This screen has a foraminous bottom 95 with small holes therein and I mount above it an upper screen 96 having larger openings therein than those in the bottom 95 and which is suspended by links 97 from the support 94. I mount on this support 94 suitable bearings 98 for an eccentric shaft 99 which carries three eccentrics, two of which are connected by straps 100 to the links 93 which support the screen 92 at one end, and the third eccentric, set at approximately 180° relative to the first mentioned eccentrics, is connected by a strap 101 to one of the links 97 which support the upper screen 96. The eccentric shaft has fast thereon a gear 103 driven by a motor 104, which motor is continuously driven during the operation of the machine and causes the screens to reciprocate constantly in opposite directions. The screens will act to sift, break up and deliver sand to the bed in advance of the grading plate 85. The screen bottom 95 is preferably formed in two longitudinal half sections hinged to the sides 92 and provided with latches 106, by means of which they are held closed. By releasing the latches the screen bottom sections will swing by gravity to the open position which is shown in dotted lines, Fig. 2, and will drop all scrap thereon.

Immediately in advance of the screens is a rotary sand elevator in the form of a bucket wheel 107 which extends the full width of the mold roller, being mounted on a shaft 108 journaled in bearing boxes 109 vertically adjustable in housings 110. The boxes are vertically adjustable by a mechanism similar to that described in connection with the vertical adjustments of the mold roller, the mechanism comprising elements 31^a, 32^a, 33^a, 34^a, 35^a, 36^a and 37^a, all corresponding respectively to similarly numbered parts 31 to 37 already described. The shafts 37^a are driven by a motor 111 suitably mounted on the motor platform 112 suitably supported on frame work 113 carried by the main frame. By means of this motor and the connections shown, the bucket wheel can be raised out of operating position. The bucket wheel is keyed fast on a shaft 108 journaled in the boxes 109 and has a drive at each end comprising a sprocket 114 fast to the wheel, a chain 115 and a sprocket 116 fast on its respective shaft 117. These shafts 117 carry gears 118 meshing gears 119 at opposite ends of the shaft of a motor 120. This motor is also mounted on the platform 112 and is driven continuously during the operation of the machine and acts to rotate the bucket wheel counter-clockwise, as viewed in Fig. 2. The wheel between the frame 1 is provided with longitudinal curved blades 121 which

connect to the circular heads of the wheel. The buckets extend from an inner cylindrical body 122 also connected to the heads and disposed concentric therewith and forming with the blades shallow 70 pockets which as the wheel rotates will pick up the molding layer of sand from the bed in advance of the sand treating mechanism and will elevate it and deposit it on the sand screen. By this arrangement practically all of the sand used in forming the molds will be taken up, worked over and returned to the bed in advance of its treatment by the plows and mold roller.

At the forward end of the machine I provide a multiple scrap plow for taking out of the sand bed any pigs or large pieces of metal or other matter left in the bed from the previous cast. The scrap plow is preferably formed by a series of plow blades 123 which are made fast at their upper end to a transverse shaft 124 which is mounted to rock in bearings 125 mounted in suitable brackets 126 underhung from the forward end of the frame 1 at each side. At an intermediate point the several plow blades are provided in front with aligning eyes 127 through which a transverse shaft or rod 128 is passed, and this rod, at suitable intervals, is connected by links 129 to rocker arms 130 which are pivotally mounted intermediate their ends by keying them on the rocker cross shaft 131 and at their inner ends which overhang within the frame they carry counter-weights 132 which counter-balance the scrap plows. The shaft 131 has connected thereto a crank 133 connected by an operating rod 134 with one of the control levers 71 on the operator's platform. By this arrangement the plows can be swung up and held out of operating position when desired.

At some suitable point on the machine frame I mount a water tank 135 which is connected by suitable piping to the sprays 136, 137, 138 and 139 which are arranged successively in the rear of the scrap plow 123, the screen 92, the pig plows 61, and at the rear end of the machine, and these several sprays are independently controllable by valve means, not shown, for the purpose of bringing the sand in bed to the desired degree of moisture for proper treatment by the mold roller, and after mold roller has formed molds.

The form of patterns on the mold roller for the cross runner and pig molds may be varied to suit the form of pigs and runners desired, provided that mold patterns are of such shape as will draw out without lifting sand from the bed. The accompanying drawings show four sets of pig mold patterns 54, which abut their respective cross runner pattern 140. Each pattern 140 for a cross runner is mounted in an indented seat or guide 141 formed in each mold roller 130

spider 142 and they are adapted to be adjusted radially in said guides in such a manner as to permit of the pattern's adjustment to give a deeper or shallower cross runner relatively to the pig molds. This construction also permits adjustment of cross runner so that either end will mold a deeper or shallower runner in relation to the pig molds connecting therewith. The patterns 141 are held in place by bolts 143, the bolt hole in the seat or pattern, as desired, being radially elongated to care for this pattern adjustment.

In practice it is found necessary when running molten metal any distance to give the main runner a certain amount of pitch. Therefore the tract on which the machine runs will be inclined to the desired pitch. It will therefore be seen that if the mold rollers were made cylindrical and the pig patterns 54 were of uniform size throughout their length as is desirable, all the pig mold imprints in the bed would be on an inclined plane parallel to the track plane. This is not desirable, and therefore the peripheral surfaces 144 of the mold roller on which the transverse rows of pig patterns 54 are mounted are not concentric with the roller axis, but are formed by a circumferential series of eccentric planes, one for each longitudinal row of mold patterns and the eccentricity of the pattern supporting planes or surfaces 144 is such that when the machine runs on an inclined track the length of one mold, each mold pattern imprint in the sand will be level. In other words, the outside surface of this roller is composed of four like pig mold planes 144, each with its cross runner pattern subtending a quarter circle of the roller and each surface is thrown out enough to bring the periphery of each mold pattern on the roller as it makes its imprint in the sand to a level plane as the machine travels down an inclined track. Obviously the amount of this eccentric displacement of the mold roller surfaces 144 will be governed by the pitch of the track on which the machine operates and the number of eccentric surfaces on the mold roller circumference will be governed by the number of mold patterns placed circumferentially in a given transverse plane about the roller. This method of forming the pig molds is best illustrated in Fig. 14 where the pig mold imprints 145 are shown lying level and connected to their respective cross runner imprint 146. The cross runner imprint does not connect with the main runner imprint 147, as in practice the cross runners are connected by hand tool to the main runner successively as the molds are filled with molten iron, the molds at the lowest level being filled first.

The worm gearing acting to raise and lower the frame 1 will give the cross runner

and pig mold patterns the requisite pitch to cause the metal to run along the same in the desired manner. The mold roller is held in position and prevented from rising up when forming molds by its own weight and by the weight of the entire machine, the roller being swung in boxes so attached to the frame that it is necessary to lift the entire weight of one end of the machine before the surface of the roller would be forced from the plane to which it had been adjusted by the worm gear operating mechanism described. Obviously additional weight can be added to the frame of the machine if needed to get the desired compression of sand to form the molds. The dotted line, Fig. 12 indicates the inclined pitch of the mold bed previous to the formation of the pig molds and the stepped horizontal benches 148 indicate the level surfaces produced successively by the eccentric surfaces 144 of the mold roller.

The travel of this machine is positive, the power being imparted to the main axle 3 by a motor drive and the axle in turn is connected to the mold roller by chain and sprocket drive of such ratio that the travel of the periphery of the mold roller surface where pig mold patterns are attached will at all times be equal to the travel of the periphery of the track wheels 2 on which the machine rests. Also, the pitch line of the gears and rack being in the same plane as the periphery of the track wheels and the gears and track wheels being of equal diameter will give an equal travel to the rack gear and to the track wheels running on the rails. The racks thus insure a positive drive and will act to prevent the machine from slipping or getting out of alignment across the mold bed.

Assuming that the machine is at one end of a bed preparatory to treating it and preparing the molds therein, its operation is substantially as follows. The scrap plows, rotary sand elevator, mold plows and mold roller are all lowered to operating position, the sand screen bottom 95 is closed, and the frame of the machine is set to the desired pitch for the cross runners. As the several motors are started up and the machine moves along the bed, the scrap plows will pick up and carry to the end of the bed pigs and large scrap left in sand from former cast. The bucket wheel elevator will lift the sand from the bed and deposit it on the shaking screens. The screens will sift the sand, removing all particles of iron or foreign matter remaining therein which are too large to pass through screens and the sand will be deposited back upon the bed. The magnet will lift out any remaining iron particles on and near the surface and the screened sand will be brought to a plane parallel with a track rail by the scraper plate attached to the sand bin. If additional sand

is needed, the sand valve will be operated to supply it and the sand will be distributed on the bed by the sand scraper. The sprays will act to moisten the sand and the moistened graded sand bed will then be acted upon by the main runner and pig mold plows, the main runner plow cutting a deep narrow trench and the pig mold plows cutting trenches which vary in depth responsive to the action of the cams on the mold roller which proportion the depth of each part of the trench to the depth of the mold imprint to be made therein. The mold roller with its patterns following the plow trenches and co-ordinating therewith will complete the molds by imparting the necessary compression and shape to the sand to form them. The displacement of sand by the mold roller, as it travels down grade along the track, to form the bed into benches, tends to build up sand at the points where the division walls come between cross runners and the row of pigs preceding them, thereby insuring a firm division wall and making lighter the duty on the patterns used to form the said wall. In order to prevent dragging of sand by the main runner pattern roller, due to its varying diameters, the latter is divided in transverse parallel planes into sections, all of which are separate from the mold roller and each capable of rotation independently of the other and of the mold roller. In this way each separate section of the main runner pattern roller 62 will travel with approximately the same peripheral speed of mold roller surface notwithstanding their different diameters.

It is desirable to leave the gears 25 loose on the shaft 3 and to use clutches 149 splined on the shaft to enable the mold roller to be disconnected from its drive shaft as the machine is run back over the bed, these clutches being preferably provided with operating connections, not shown, to the operator's platform. This will prevent driving the cams operating the plow lifting cranks when the plows are not in service.

It is to be understood that the mold roller can be fabricated any desired manner or cast integrally or in sections; and that the machine can be driven by electrical or other power.

The scrap plows are flattened out at their forward ends so that they will receive and support the larger pieces of iron and other matter which they are intended to collect from the bed as the machine advances.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a pig bed molding machine, a wheeled frame movable on tracks, a mold roller journaled in said frame, and means to adjust the height of the frame relative to the tracks to control the inclination of the roller. 70

2. In a pig bed molding machine, a wheeled frame movable on tracks, a mold roller mounted in vertically adjustable journals in the frame, and means to adjust a side of the frame relative to its tracks to control the inclination of the roller. 75

3. In a pig bed molding machine, a traveling frame, a mold roller journaled therein and having patterns to produce the pig mold imprints in the sand bed, vertically reciprocable plow means in advance of the mold roller, and a common co-ordinated drive for plows and roller adapted to move the plows to vary the depth of their furrows proportionately with the height of the following mold patterns to obtain substantially uniform compression of the mold bed. 80 85 90

4. In a pig bed molding machine, the combination with a traveling frame having a mold roller journaled therein, and track supports for the frame, of plow means disposed in advance of the roller and at such an angle as to pick up and remove larger pieces of metal from the sand. 95

5. In a pig bed molding machine, the combination with a traveling frame having a mold roller journaled therein, and tracks for the machine, of means to pick up and screen the upper layer of sand in the bed in advance of said mold roller. 100

6. In a pig bed molding machine, the combination with a traveling frame having a mold roller journaled therein, and tracks for the machine, of means to screen from the upper layer of sand in the bed large particles of metal and foreign matter. 105

7. In a pig bed molding machine, the combination with a traveling frame having a mold roller journaled therein, and tracks for the machine, of magnetic means to remove from the surface of the bed to be molded small metallic particles remaining therein. 110 115

8. In a pig bed molding machine, the combination with a traveling frame having a mold roller journaled therein, and tracks for the machine, of plow means to collect and carry off the largest pieces of foreign matter in the sand, and means to screen out of the sand other pieces of metal and foreign matter remaining therein. 120

9. In a pig bed molding machine, the combination with a traveling frame having a mold roller journaled therein, and tracks for the machine, of means to screen the upper layer of the sand bed for the removal of larger pieces of metal and foreign matter, and magnetic means to remove from the 125 130

screened sand finer metallic particles remaining therein.

10. In a pig bed molding machine, the combination with a traveling frame having 5 a mold roller journaled therein, and tracks for the machine, of plow means acting to collect and carry off the largest pieces of metal remaining in the bed, means to screen the upper layer of the sand for the further removal 10 therefrom of pieces of metal and foreign matter, and magnetic means to remove from the screened sand fine metallic particles remaining therein.

11. In a pig bed molding machine, the combination with a traveling frame having 15 a mold roller journaled therein, of a transverse series of scrap plows mounted at the forward end of the machine and shaped and inclined at such an angle as both to plow 20 up the bed and to pick up and carry off large metal pieces remaining in the bed, and means to raise said scrap plows out of operating position.

12. In a pig bed molding machine, the combination with a traveling frame having 25 a mold roller journaled therein, of a screening mechanism disposed transversely across the machine, a transversely disposed bucket wheel, means to pick up the top layer of 30 sand and deliver it to said screen mechanism for treatment in advance of said roller, and adjustable bearings to set said bucket wheel to pick up the sand above a predetermined grade level.

13. In a pig bed molding machine, the combination with a traveling frame having 35 a mold roller journaled therein, of means to prepare the sand bed for molding in advance of the roller, a scraper to grade the bed, and means carried by the machine for delivering a replacement supply of sand to the pig bed in advance of the scraper.

14. In a pig bed molding machine, the combination with a traveling frame having 45 a mold roller journaled therein, of means to primarily plow up and grade the mold bed to prepare it in advance of the roller, a sand bin extending transversely across the machine, and means to feed a replacement supply 50 of sand therefrom to the bed.

15. In a pig bed molding machine, the combination with a traveling frame having a mold roller journaled therein, of means to primarily plow up and grade the mold bed 55 to prepare it in advance of the roller, a sand bin extending transversely across the machine, and means to feed a replacement supply of sand therefrom to the prepared bed immediately in advance of the scraper.

16. In a pig bed molding machine, the combination with a traveling frame having 60 a mold roller journaled therein, of means to remove the larger pieces of metal and foreign matter from the sand bed, scraper means to grade the bed, and plows to open

furrows in advance of raised patterns on the mold roller.

17. In a pig bed molding machine, the combination with a traveling frame having a mold roller journaled therein, of plow 70 means disposed to open furrows in advance of the raised patterns on mold rollers, and means to vary the depth of the plow furrows proportionately to the depth of the mold imprints to be made therein. 75

18. In a pig bed molding machine, a traveling frame, a mold roller journaled therein and having pig, cross runner and main runner patterns thereon, a fixed plow to open the bed in advance of the main 80 runner pattern, intermittently reciprocable plows disposed in alignment with and in advance of the pig patterns, and operating means to reciprocate said latter plows in co-ordination with the mold roller to vary 85 the depth of the pig mold furrows cut by them.

19. In a pig bed molding machine, a traveling frame, a mold roller journaled therein and having patterns for producing 90 the pig mold imprints in the sand bed, plows to open furrows in line with each pig mold pattern, a cam on the mold roller, and mechanism operated by the cam to raise and lower 95 said plows to vary the depth of their furrows in substantial proportion to the height of the pattern where it enters the furrow.

20. A pig bed molding machine comprising a frame having wheels and tracks therefor, a mold roller journaled in the frame, a rack and pinion drive to advance the frame on said tracks, the pitch circumference of the pinions and the tread circumference of the wheels being equal, and a drive for the pinions and mold roller adapted to give 100 both the same peripheral velocity. 105

21. A pig bed molding machine in accordance with claim 20, in which the mold roller has raised patterns rising in a plane 110 parallel with the direction of movement of the frame and having the ends of the raised patterns tapered to enter and leave the sand bed without breaking same, notwithstanding their greater peripheral velocity than that of the mold roller. 115

22. A pig bed molding machine comprising a vertically adjustable mold roller, wheel supports for the machine, tracks for said wheels, racks alongside the tracks, pinions engaging the racks, a driving motor in 120 the machine, driving connections from the motor to the mold roller and to the pinions adapted to give both the same peripheral speeds, a high speed reverse drive for the pinions, and clutch means controlling the 125 drives to the pinions.

23. A pig bed molding machine comprising a vertically adjustable mold roller, wheel supports for the machine, tracks for said wheels, racks alongside the tracks, pinions 130

engaging the racks, a driving motor in the machine, driving connections from the motor to the mold roller and to the pinions adapted to give both the same peripheral speeds, a high speed reverse drive for the pinions, and clutch means controlling the drives to the pinions and roller.

24. In a pig bed molding machine, a mold roller having at one end a main runner mold wheel mounted to rotate independently of the mold roller, said main runner wheel being divided in transverse planes at right angles to its axis into independently rotatable sections.
- 10 25. In a pig bed molding machine, a mold roller having longitudinal series of spaced pig mold patterns, and a longitudinal cross runner pattern associated with each longitudinal row of pig patterns and mounted 20 for radial adjustment in the roller.
26. In a pig bed molding machine, a mold roller journaled therein and provided with longitudinal series of peripheral pig mold patterns, a cross runner pattern associated 25 with each longitudinal row of pig mold patterns, and independent means to adjust said runner pattern both radially and angularly relatively to the axis of the roller.
27. In a pig bed molding machine, a frame 30 having a mold roller journaled therein, wheels for supporting the frame, axles on which said wheels are mounted, and journal boxes for the axles vertically adjustably connected to the frame.
- 35 28. In a pig bed molding machine, a frame having a mold roller journaled there-

in, wheels for supporting the frame, axles on which said wheels are mounted, and journal boxes for the axles vertically adjustably connected to the frame by means of 40 pairs of links which straddle the frame and at their lower ends engage each journal box at each end and at their upper ends are connected to screw adjusted cross heads adjustably mounted on the frame. 45

29. In a pig bed molding machine, a traveling carriage, a mold roller journaled therein, a sand elevating bucket wheel substantially equal in length with the roller, means to drive said wheel, a shaking screen to receive the sand from said wheel, which screen is substantially co-extensive in length with the roller, and means to drive the screen. 50

30. In a pig bed molding machine in accordance, with claim 29, in which the screen comprises reversely reciprocable upper and lower screens with the lower screen provided with a sectional drop bottom, and means to hold the bottom in closed position 60 during the operation of the screen. 55

31. In a pig bed molding machine, the combination with a traveling frame having a mold roller journaled therein, of means independently adjustable to agitate and grade the sand bed in advance of the roller, means to supply replacement sand to maintain the desired grade level of the bed, and means to moisten the sand. 65

In testimony whereof I affix my signature.

SAMUEL STEWART.
